Primary Examiner—A. Hugo Word*Assistant Examiner*—Cathy Anne MacCormac*Attorney, Agent, or Firm*—Leon Gilden**[57] CLAIM**

The ornamental design for a dog transport safety rig for pickup trucks, as shown and described.

DESCRIPTION

FIG. 1 is a right end elevational view of a dog transport safety rig for pickup trucks showing my new design; FIG. 2 is a left end elevational view thereof; FIG. 3 is a side elevational view thereof; FIG. 4 is another side elevational view thereof; FIG. 5 is a third side elevational view thereof; FIG. 6 is a fourth side elevational view thereof; FIG. 7 is an enlarged, fragmentary view thereof taken near the left side of FIG. 3; FIG. 8 is an enlarged fragmentary view thereof taken in the middle of FIG. 3; FIG. 9 is an enlarged, fragmentary view thereof taken at the right side of FIG. 3; and, FIG. 10 is a perspective view thereof, the broken lines are for purposes of illustration only and form no part of the claimed design.

FIG. 1

FIG. 2
